UNITED STATES PATENT OFFICE.

CORNELIUS D. EHRET, OF ARDMORE, PENNSYLVANIA.

WIRELESS SIGNALING SYSTEM.

1,080,544.

Specification of Letters Patent.

Patented Dec. 9, 1913.

Application filed December 7, 1903. Serial No. 184,223.

To all whom it may concern:

Be it known that I, CORNELIUS D. EHRET, a citizen of the United States, residing at Ardmore, county of Montgomery, and State of Pennsylvania, have invented certain new and useful Improvements in Wireless Signaling Systems, of which the following is a specification.

My invention relates to receiving apparatus to be employed in systems wherein messages or signals are transmitted through the natural media through the agency of electro-radiant energy.

My invention resides in a wave responsive device or detector which consists of a condenser device in which the dielectric mass or medium is such as to manifest dielectric hysteresis.

My invention resides also in such wave responsive device in combination with other apparatus and circuit arrangements at the receiving station of a wireless signaling system.

My invention resides also in circuit arrangements hereinafter pointed out.

As is well understood in the electrical arts, there is a hysteresis loss or effect in the material forming the dielectric of a condenser. The dielectric substance is subjected to increasing and decreasing electric strains and in consequence thereof there is certain energy loss in carrying the dielectric substance through the cycles or variations of electric strain. Some substances, though very good insulators, are unsuitable as the dielectric media for condensers as ordinarily employed in the electrical arts because their dielectric hysteresis effects are so great as to cause their undue heating and therefore unsuitability for service in the condenser.

The hereinafter described apparatus is believed to involve the principle of dielectric hysteresis, the high frequency oscillations being believed to change or vary the hysteresis effect thus causing a change in the capacity of the condenser, and so causing manifestation in the telephone or other signal translating instrument. While giving this as a tentative theory merely, the invention, nevertheless, may be understood by the following description.

Reference is to be had to the accompanying drawing, in which the drawing is a diagrammatic view of a receiving apparatus employing a condenser like device whose dielectric medium is of rubber or the like.

In the drawing A represents an aerial

conductor in series with which and the earth plate E is a condenser device whose metallic or conducting armatures 1 and 3 are separated by the dielectric medium 2 of rubber or any other material in which the dielectric hysteresis effect is relatively great. In shunt to this condenser device is a local circuit including the source of varying or alternating currents 6, the telephone receiver 7 and the choke coils 4 and 5. In this arrangement the source 6 is capable of supplying an alternating or varying electromotive force of approximately 400 or 500 volts and of a periodicity or frequency such that a telephone receiver will not respond thereto. The frequency of the source 6, and its voltage, or both of them, is so adjusted that an effect in the telephone receiver is just impending. Upon the reception of electro-radiant energy the effect of such energy upon the dielectric hysteresis of the substance 2 is such as to change the dielectric hysteresis effect and thereby change in effect the capacity of the condenser device, causing a change in amount of or permitting a greater flow of energy through the local circuit including the telephone receiver 7 and thereby causing a response in said telephone receiver. Such response of the telephone receiver corresponds with the reception of the electro-radiant energy, persists so long as the electro-radiant energy continues to arrive, and ceases when the electro-radiant energy ceases.

In general, for the dielectric of the condenser device I prefer to use such substance or substances as have relatively great dielectric hysteresis effects; though the system is operative when a substance having lower dielectric hysteresis effect is employed.

Though I have shown the condenser device connected directly in the aerial conductor it is obvious that the condenser device may be connected in a receiving circuit which is in inductive relation with the aerial conductor; the condenser device may obviously be connected in any relation that will bring it under the influence either directly or indirectly of the received electro-radiant energy.

What I claim is:

1. In a wireless signaling system, receiving apparatus comprising a condenser wave responsive device, a receiving conductor or circuit associated therewith, a source of fluctuating current in a local circuit includ-

ing said wave responsive device, and means responsive to changes in said fluctuating current for producing a signal.

2. In a wireless signaling system, receiving apparatus comprising an aerial conductor, a condenser associated therewith as a wave responsive device, and a local circuit including said condenser, a source of fluctuating current, and a signal translating instrument.

3. In a wireless signaling system, receiving apparatus comprising an aerial conductor, a condenser associated therewith as a wave responsive device, a local circuit including a source of fluctuating current for producing dielectric hysteresis in said condenser, and a signal translating instrument operative upon changes in the dielectric hysteresis effect caused by received electro-radiant energy.

4. In a wireless signaling system, an aerial conductor, a condenser wave responsive device associated therewith, a local circuit including said wave responsive device, a source of fluctuating current, and a telephone receiver.

5. In a receiver system for electro-radiant energy, the combination with a capacity exhibiting device, of means for subjecting the same to the received energy, and a circuit including said device, a source of current and a signal translating instrument.

6. In a wireless signaling system, an aerial conductor, a condenser associated therewith as a wave-responsive device and subjected to the effects of the received electro-radiant energy, a circuit including said condenser, a telephone and a source of fluctuating current, the rate of fluctuation of the current delivered by said source being such as to be inaudible in said telephone.

7. In a wireless signaling system, receiving apparatus comprising a condenser as a wave-responsive device, a signal translating instrument, and a source of fluctuating current, said signal translating instrument being insensitive to the rate of fluctuation of said fluctuating current.

8. In a wireless signaling system, the combination with a receiving conductor, of a wave-responsive device associated therewith, and manifesting an electrostatic capacity reaction, and a local source of fluctuating energy associated with said wave-responsive device.

9. The method of transmitting intelligence electrically, which consists in impressing upon the natural media electro-radiant energy representing a signal or message, transforming the received energy into the energy of charges or currents, subjecting a material to fluctuating electrostatic strains, subjecting said material to said currents or charges, and translating a signal or message from the resultant effects.

10. In a wireless signaling system, the combination with an aerial conductor, of a wave-responsive device associated therewith, and a local circuit including said wave-responsive device a telephone and a source of fluctuating current.

11. In a wireless signaling system, the combination with a receiving conductor, of a condenser associated therewith as a wave-responsive device, and a local source of fluctuating energy continuously acting upon said condenser.

12. In a wireless signaling system, the combination with a receiving conductor, of a wave-responsive device associated therewith and capable of manifesting a capacity reaction, and a local source of fluctuating voltage coöperating with said wave-responsive device.

13. In a wireless signaling system, the combination with a receiving conductor, of a wave-responsive device associated therewith and capable of manifesting a capacity reaction, a local source of fluctuating voltage coöperating with said wave-responsive device, and a signal translating instrument.
